CAR TRUCK SIDE FRAME

Charles R. Busch, Orange, N. J., assignor to Buffalo Brake Beam Company, New York, N. Y., a corporation of New York

Original application March 15, 1937, Serial No. 130,881. Divided and this application August 7, 1937, Serial No. 157,863

4 Claims. (Cl. 105—206)

The present invention relates to the construction of side frames of railway car trucks which may be of any suitable design, but specially trussed and reinforced so as to impart greater strength to the castings, more particularly but not necessarily to adapt the side frames for guiding the ends of a brake beam thereupon, as disclosed in my previous application filed March 15, 1937, Serial No. 130,881, of which this application is a division.

With these objects in view, the invention consists of certain features of construction and combinations of parts to be hereinafter described and then claimed with reference to the accompanying drawings illustrating a preferred embodiment of the invention and wherein

Fig. 1 is a plan view of so much of a car truck side frame as is necessary to illustrate the present invention, and partly in broken lines;

Fig. 2 is a side elevation of the parts shown in Fig. 1, partly in broken lines;

Fig. 2a is a fragmentary side elevation of parts shown in Fig. 2, and accompanied by dot and dash indicator lines intersecting the axis of a wheel axle;

Fig. 3 is a detail section on the line 3—3, Fig. 1, looking in the direction of the arrows and showing in section a suitable brake beam;

Fig. 4 is a section on the line 4—4, Fig. 2, looking in the direction of the arrows, and showing one end of a brake beam in section;

Fig. 5 is a view of side frame parts broken away, looking towards the inner sides thereof, the brake beam being shown in section, and parts being shown in broken lines, and

Fig. 6 is a sectional elevation on the line 6—6, Fig. 2, in the direction of the arrow.

In the drawings, there is illustrated only so much of the car-truck side frame 10 as is necessary to illustrate the improvements. The side frame may be of any suitable design, although it is preferred that it be constructed in trussed form having a compression member 11 and a tension member 12. Fig. 2 shows the car truck side frame broken away at about its mid-length, so that there is illustrated only one bolster guiding column 13. The other half of the side frame not illustrated will be constructed according to the portion thereof which is shown and described herein. The frame 10 has its tension member 12 provided with spring supporting brackets 14 which may be used to support a spring plank if one is used.

The drawings illustrate a recess 15 extending along the inner wall of the side frame, such re-

cess extending preferably at an angle of approximately twelve degrees to the horizontal for guiding a brake beam, only if it be intended to guide the same upon the side frames in accordance with what is shown, described and claimed in my said previous application. Fig. 2a of the drawings specifically and graphically discloses the preferred angle of 12 degrees for the said recess 15 or its equivalent. The axis C of the wheel axle 20 shown in broken lines preferably indicates the point from which the degree of angle of the recess 15 is determined. The dot and dash line H indicates the horizontal which is parallel with the car track, and the dot and dash line A indicates an angle of 12 degrees to the horizontal. It is of course within the scope of the present invention to change this degree of angularity A and to otherwise deviate from what is graphically indicated by A, C and H. The point C might of course be elsewhere than to indicate the wheel 20 axis, but in any event the recess 15 is at an angle to the horizontal. Such recess 15 is preferably defined by guide flanges 16, 17 cast or formed integrally with the side frame. These inner ribs or flanges greatly strengthen the tension member 12 and the lower end of guide column 13, especially where the latter meet or intersect. Where such guide flanges are employed it is desirable to back them up or strengthen them as by means of ribs or brackets 18 and 19 which are cast integrally with the side frame. The brackets 18 converge toward their upper ends with respect to the guide flange 16 and the brackets 19 extend downwardly from guide flange 17, both sets of brackets gradually merging with the side frame. If the brake beam is to be so guided, the brackets 19 assist in absorbing any downward pressure or thrusts and the brackets 18 any upward thrust from the brake beam. That end of recess 15 which would be nearest to a car wheel is closed by a transverse wall 20 so as to confine the brake beam in its forward movement in applying the brake shoes, the opposite end of the recess being left open to permit the removal of the beam.

Inasmuch as in practice the tendency now is to make car truck side frames wider or thicker than heretofore so as to strengthen the same, it is preferred that each recess 15 in the side frame extends inwardly beyond the plane of the inner surface of the side frame so that the intermediate inner wall of the recess is disposed between the vertical planes of the inner and outer surfaces of the side frame, as shown in Figs. 4 and 6. This increases the bearing surface for the end of the beam whether the flanges or ribs 16, 17 extend in-

wardly as far as shown in the drawings or do not extend so far, and even if in practice the side frames were not as thick as is now the tendency to make them, the flanges or ribs 16, 17 reinforce and impart additional strength to the recessed portion of the side frame.

Referring to Fig. 1 which shows the end of the beam 15 as engaged with the guide, and also referring to Fig. 3, it is apparent that the beam is allowed a distance of travel on the guide, when applying and releasing the brake, which is substantially equivalent to the distance between the inner wall of the adjacent guide column at the bolster window opening and the wall or stop 20 at that end of the guide which is closest to the car wheel, and in fact at that end of the guide which is laterally opposite to the tread of the adjacent car wheel. The width of the guide is shown in Figs. 1, 4 and 5 and such width is maintained for substantially its entire length to provide sufficient bearing support for guiding the beam in its necessary range of travel. More specifically the same width of guide should be maintained substantially throughout its entire length in order to provide maximum bearing surface for the beam in its travel from full release position to that of full braking pressure, so that the inner edges of the guide will extend substantially parallel with the adjacent outer surface of the side frame, as clearly shown in Figs. 1 and 4. The length of the guide is also based upon a sufficiency of length to allow for the maximum wear on the car wheel and on the brake shoe. That end of the guide which is closest to the car wheel is inwardly offset as shown in Fig. 1 as a precaution, in case of excessive lateral wheel approach to the guide.

Referring to Figs. 2, 4 and 5, the frame 10 is shown as trussed along its upwardly inclined tension portion by means of a relatively narrow reinforcing bottom portion 21 which is cast or formed integrally with the side frame, and which reinforcing portion defines corresponding surfaces at the interior of the hollow side frame, and of course the corresponding inclined portion (not shown) of the tension member of the side frame will be correspondingly reinforced. As such trussing or reinforcing portions are in the intermediate regions of the guiding recesses in the side frame, the walls of the recesses are considerably strengthened at points where the weight and any downward movement of the brake beam is imposed upon the side frame. Preferably, each reinforcement tapers toward its upper end.

To further strengthen or reinforce the tension member 12 of the side frame, the same is cast with a vertical reinforcing web 22 of suitable thickness, which extends for a suitable distance along the hollow interior of the tension member, thereby fortifying the added strength given by such reinforcing bottom portions as 21 of the tension member.

Therefore, not only is the tension member reinforced and strengthened at each end by the bottom reinforcement 21, but by the interior reinforcing element or web 22, the same mutually contributing to the reinforcement of the strength of the hollow, cast tension member 12.

Inasmuch as the preferred construction is illustrated it will probably be found useful to those skilled in the art if the illustrated construction be more specifically described as follows:

The recess 15 in the tension member may be defined by the ribs or flanges 16, 17, but in any event it may best be located at the inner side of the tension member so as to face inwardly there-

from. The flange 17 or its equivalent will support one end of the brake beam, if that is required, and whether or not the brake beam is to be guided and supported by the side frame such rib 17 or 16 or both act to reinforce the tension member, and thereby strengthen the same along lines inwardly from the preferred hollow interior of the tension member, or at the outer exposed surface of the tension member. Preferably the reinforcing rib or flange 16 or 17 extends upwardly along the inclined portion of the tension member from a point close to the spring seat 14 so that a guided brake beam will be detained by the spring seat if it should tend to fall back inwardly. As shown, the reinforcing ribs 16, 17 extend from the inclined portion of the tension member across the lower end of the column 13 which is directly adjacent the said upwardly inclined portion of the tension member, so that the said column is reinforced at its inner side, that is, upon its outside.

Preferably the reinforcing bottom portion 21 is a partial cross-section of the main body of the tension member, and such reinforcement 21 extends from a point on the tension member which is located below a guide column and upwardly, so as to form the bottom of the tension member, to a point adjacent the upper end of the inclined portion of the tension member as shown more fully in Figs. 2 and 5. The reinforcement 21 may be seen at the outside of the tension member and in the preferred form of the invention the only interior reinforcement of the tension member is by means of the web 22, thereby simplifying the production of the casting, and then only the reinforcement 22 would be in the hollow interior of the casting, any other reinforcement of the tension member being preferably exposed at the outside thereof. It will be noted that the web or reinforcement 22 at the interior of the tension member is within the inclined portion thereof and hence that such reinforcement will be under tension.

It will be obvious to those skilled in the art that the invention shown and described is susceptible of more or less modification without departing from the spirit of the invention as defined in the appended claims.

What I claim as new is—

1. A car-truck side frame having a closed hollow inclined tension member, and a reinforcing vertical web in the inclined portion of the tension member.

2. A car-truck side frame having a hollow inclined tension member, and a reinforcing web in the tension member and extending in a vertical plane between the upper and lower walls of the inclined portion thereof.

3. A car-truck side frame having a hollow tension member provided with a narrowed reinforcing bottom portion extending lengthwise thereof and defining a part of the surface of the interior of the tension member, and such member having within it longitudinal reinforcing means integral with such surface.

4. A car-truck side frame having a hollow tension member provided with a narrowed reinforcing bottom portion extending lengthwise thereof and defining a part of the surface of the interior of the tension member, and such member having within it a longitudinal reinforcing web integral therewith and connecting opposite portions of such surface.
